CLAIM

The ornamental design for a flashlight, as shown and described.

DESCRIPTION

FIG. 1 is a perspective view including a top, right side and rear of the first embodiment of a flashlight showing my new design;

FIG. 2 is a top plan view of the flashlight of FIG. 1;
FIG. 3 is a bottom plan view of the flashlight of FIG. 1;
FIG. 4 is a left side elevation view of the flashlight of FIG. 1;
FIG. 5 is a right side elevation view of the flashlight of FIG. 1;

FIG. 6 is a front elevation view of the flashlight of FIG. 1;
FIG. 7 is a rear elevation view of the flashlight of FIG. 1;
FIG. 8 is a perspective view including a top, right side and rear of the second embodiment of a flashlight showing my new design;

FIG. 9 is a top plan view of the flashlight of FIG. 8;
FIG. 10 is a bottom plan view of the flashlight of FIG. 8;
FIG. 11 is a left side elevation view of the flashlight of FIG. 8;
FIG. 12 is a right side elevation view of the flashlight of FIG. 8;

FIG. 13 is a front elevation view of the flashlight of FIG. 8;
FIG. 14 is a rear elevation view of the flashlight of FIG. 8;
FIG. 15 is a perspective view including a top, right side and rear of the third embodiment of a flashlight showing my new design;

FIG. 16 is a top plan view of the flashlight of FIG. 15;
FIG. 17 is a bottom plan view of the flashlight of FIG. 15;
FIG. 18 is a left side elevation view of the flashlight of FIG. 15;

FIG. 19 is a right side elevation view of the flashlight of FIG. 15;

FIG. 20 is a front elevation view of the flashlight of FIG. 15;
and,

FIG. 21 is a rear elevation view of the flashlight of FIG. 15.
(Continued)

The broken lines represents portions of the flashlight that form no part of the claim.

1 Claim, 21 Drawing Sheets
